UNITED STATES PATENT OFFICE

2,578,211

SIDE BAR CYLINDER LOCK

Roy Clifton Spain, Salem, Va., assignor to The
Yale & Towne Manufacturing Company, Stamford, Conn., a corporation of Connecticut

Application July 16, 1948, Serial No. 38,969

12 Claims. (Cl. 70—366)

1

This invention relates to a lock, and more particularly to that type of lock in which a key plug moves relatively to a housing that frequently takes the form of a cylinder. More particularly, my invention relates to that type of lock of the particular class in which the movement of the key plug is controlled by a side bar that in turn is controlled by a series of tumblers.

In the usual side bar lock, a series of tumblers is manipulated by a key relatively to the key plug. If the tumblers are properly set, a side bar that normally rests partially within a groove or the like in the cylinder and partially within the key plug, is moved entirely out of the groove in the cylinder and entirely within the area defined by the periphery of the key plug. Obviously, the key plug and the side bar are then movable together to any position desired.

It is the object of my invention to contribute a lock of the particular class in which picking will be made extremely difficult. As a feature whereby this object of my invention is attained, I make it possible for my key plug to move a limited degree relatively to the cylinder from what I term an initial central position. Upon application of picking torque to the key plug, this limited rotation of the key plug takes place, and the side bar is then held against movement into that zone defined by the periphery of the key plug. As a further feature of this part of the invention, surfaces are provided on the key plug for movement into holding relation to the side bar for holding the side bar in locking position so long as the key plug is moved away from said initial central position.

In my lock, I prefer to use a rotating plug and rotary tumblers that are set by the endwise movement of the key into the key plug. Those skilled in the art will appreciate that it is possible to arrange the mechanism so that other types of plugs, and tumblers otherwise mounted, may be utilized. In addition, my tumblers are so mounted in the key plug that their peripheries lie inwardly of that area encompassed by the periphery of the key plug. Still further, as a feature of my invention the tumbler peripheries are available to the side bar only within the extremely short angular zone defined by a groove in the key plug into which the side bar is adapted to move upon the setting of the tumblers. As a still further feature of this part of the invention, the side bar of my lock is formed as a simple cylindrical pin.

I have thus outlined rather broadly the more important features of my invention in order that the detailed description thereof that follows may

2

be better understood, and in order that my contribution to the art may be better appreciated. There are, of course, additional features of my invention that will be described hereinafter and which will form the subject of the claims appended hereto. Those skilled in the art will appreciate that the conception on which my disclosure is based may readily be utilized as a basis for the designing of other structures for carrying out the several purposes of my invention. It is important, therefore, that the claims to be granted me shall be of sufficient breadth to prevent the appropriation of my invention by those skilled in the art.

15 Referring now to the drawings, Fig. 1 is a perspective view of the cylinder of my invention and a securing nut utilized in connection therewith. Fig. 2 is a view looking downwardly on the cylinder of Fig. 1. Figs. 3, 4, and 5 are sections taken along lines 3—3 of Fig. 2 showing the parts in different operating positions. Fig. 6 is a plan view of the key plug per se of my invention, while Fig. 7 is a perspective view of the side bar formed as a cylindrical pin. Fig. 8 is a section taken along lines 8—8 of Fig. 6.

20 Referring now more particularly to the drawings, the cylinder of my invention is designated by reference numeral 10 and within this cylinder I mount for rotation a key plug 11, the cylinder 10 having a bore 12 therethrough in which the key plug 11 is adapted to rotate. At this point it is important to indicate that frequently the cylinder will take the form of a handle equipped with a bore, or some other type of housing, all as those skilled in the art will fully appreciate. In the drawings the cylinder 10 is of that type adapted to be secured in a housing by a nut 10a threaded thereon.

25 Key plug 11, as best seen in Fig. 6, is formed with a head 13 at its forward end and with a keyway 14 extending longitudinally therethrough. At its rear end the key plug has a groove 15 into which fits a retainer 16 as best shown in Fig. 2, the retainer lying partially within the groove 15 and against the end surface 17 of the cylinder 10 so as to retain the key plug against endwise movement outwardly of the cylinder 10.

30 Key plug 11 is further formed with a series of tumbler grooves 18 in each of which lies a tumbler 19. The tumbler grooves 18 are so formed as to present an end surface 20 against which presses one end of a spring 21. The other end of each of the springs 21 in the several tumbler grooves 18 presses against a tumbler 19 mounted in each groove. The tumblers 19 are adapted

for rotation about a pin 22 positioned longitudinally within the key plug 11, it being obvious that the tumblers will be urged in a counterclockwise direction about the pin 22 by the several springs 21. Each tumbler is equipped with a shoulder 23 that is pressed against a stop surface 24 of each of the tumbler grooves 12 whereby to limit the counterclockwise rotation of the several tumblers. The shoulders 23 are contacted by a key K inserted in the keyway 14 as best shown in Fig. 4 whereby to rotate the tumblers against the force of the springs 21. This rotation of the tumblers by the key K is intended to position the several gatings 25 of the tumblers in alignment with a deep release groove 26 formed longitudinally in the key plug 13.

The bore 12 of the cylinder 10 has formed therein a longitudinal locking groove 27, and co-operable with the locking groove 27 of the cylinder and the release groove 26 of the key plug 11, is a cylindrical pin 28 forming the side bar of my lock. A spring 29 is staked into position at 30 relatively to the cylinder 10 and bears at 31 against the pin 28 whereby to urge the said pin radially out of the locking groove 27 of the cylinder 10 and into the release groove 26 of the key plug 11. Those skilled in the art will understand, of course, that when the several tumblers 19 are properly set by the key K, the several gatings 25 of the tumblers will be in alignment with the release groove 26 of the key plug, so that the cylindrical pin 28 will move into the release groove 26 as well illustrated in Fig. 4. Thereafter, the key plug together with the side bar will be rotatable either in a clockwise or counterclockwise direction.

The key plug 11, as best seen in Figs. 6 and 8, is formed with relatively shallow grooves 32 at each side of the relatively deeper release groove 26. The shallow grooves 32 are of such size that they permit rotation of the key plug 11 relatively to the cylinder 10 for some slight distance clockwise and counterclockwise from the central position of Figs. 3 and 4. This rotation is well illustrated in Fig. 5. It will be noted, however, from Fig. 5, that once the key plug is rotated as permitted by one of the shallow grooves 32, the deep release groove 26 is withdrawn from opposite the pin 28. Also, that sector of the key plug in which the tumblers are available to the side bar is moved away from opposite the side bar. Therefore, in Fig. 5, even if the several tumblers are aligned with their gatings opposite the pin 28, as is actually the case in Fig. 5, the locking pin will be held against movement into release position into the gatings. Therefore, it becomes impossible to pick the lock after the application of picking torque thereto.

I believe that the construction of my invention will be made clearer by a simple review of one authorized key operation of the lock and also a description of what happens when an attempt is made to pick the lock. Let us first consider the locking mechanism in its initial position with the key out of the keyway 14 and the several tumblers held by the springs 21 in a fully rotated counterclockwise position as shown in Fig. 3. In Fig. 3 the side bar or cylindrical pin 28 is held by the peripheries of the tumblers within the locking groove 27 of the cylinder and against movement into the deep release groove 26. If a proper key K is now inserted into the keyway 14, the tumblers will be rotated to the position of Fig. 4 to align their several gatings 25 with the deep release groove

26. The spring 29 will now press the pin 28 into the aligned gatings and into the deep release groove 26. Key plug 11 will now be free for rotation. This is the action of the mechanism when properly key operated.

Let us now consider the parts of Fig. 3 in order to see just what happens if an attempt is made to pick the lock. First, the lock picker must apply picking torque; that is, rotate the key plug to the limit permitted by the shallow grooves 32. Unless picking torque is applied to a key plug, it is actually impossible to "feel" the locking action. If picking torque is applied in a counterclockwise direction, the key plug will rotate to the position of Fig. 5.

With the parts in the position of Fig. 5, even if the tumblers are properly and fully picked as is actually illustrated in Fig. 5, it is impossible to rotate the key plug further in a counterclockwise direction. It becomes necessary, in order to permit the locking pin 28 to move to release position in release groove 26, to rotate the key plug back to the position of Fig. 3. Of course, while this is being done, the tumblers are released from whatever picking tool has been utilized, and the lock mechanism is restored to its original locking condition.

I believe that the rather considerable merit of my invention and its operation will now be clear to those skilled in the art.

I now claim:

1. In a lock of the class described, a cylinder, a key plug rotatable in a bore of said cylinder, a series of tumblers carried by said key plug and movable relatively thereto by a key so as to be positioned in accordance with the bittings of said key, said tumblers having gatings adapted for alignment when said tumblers are set by a properly bitted key, a side bar operatively positioned relatively to a groove formed in the bore outlining surface of said cylinder and also a groove of said key plug adapted for the full entry of said side bar therein to release said key plug for rotation, the tumblers holding said side bar against full entry into said key plug groove until said gatings are in alignment with said key plug groove through the proper positioning of said tumblers, said key plug groove having a shallow extension at the side thereof to permit said key plug to rotate relatively to said cylinder and side bar as permitted by said shallow extension.

2. In a lock of the class described, a cylinder, a key plug movable in a bore of said cylinder, a series of tumblers carried by said key plug and movable relatively thereto by a key so as to be positioned in accordance with the bittings of said key, said tumblers having gatings adapted for alignment when said tumblers are set by a properly bitted key, a side bar operatively positioned relatively to a groove formed in the bore outlining surface of said cylinder and also a groove of said key plug adapted for the full entry of said side bar therein to release said key plug for movement, the tumblers holding said side bar against full entry into said key plug groove until said gatings are in alignment through the proper positioning of said tumblers, and said key plug groove having a shallow extension to permit said key plug to move relatively to said cylinder and side bar as permitted by said shallow extension.

3. In a lock of the class described, a cylinder, a key plug rotatable in a bore of said cylinder, a series of tumblers carried by said key plug and

movable relatively thereto by a key so as to be positioned in accordance with the bittings of said key, said tumblers having gatings adapted for alignment when said tumblers are set by a properly bitted key, a side bar operatively positioned relatively to a groove formed in the bore outlining surface of said cylinder and also a groove of said key plug adapted for the full entry of said side bar therein to release said key plug for rotation, tumblers holding said side bar against full entry into said key plug groove until said gatings are in alignment with said key plug groove through the proper positioning of said tumblers, said key plug groove having a shallow extension at the side thereof to permit said key plug to rotate relatively to said cylinder and side bar as permitted by said shallow extension, the said shallow extension being not as deep as said tumbler gatings and thereby holding the side bar out of said tumbler gatings and in said cylinder groove even if the tumbler gatings are aligned relatively to said shallow extension, whereby to require the return of said key plug to align its groove with said cylinder groove and the setting of said tumblers as a prerequisite to the release of said key plug for free rotation in said cylinder bore.

4. In a lock of the class described, a cylinder, a key plug rotatable in a bore of said cylinder, a series of tumblers carried by said key plug and movable relatively thereto by a key so as to be positioned in accordance with the bittings of said key, said tumblers moving in said key plug with their peripheral surfaces spaced at all times from the periphery of said key plug, said tumbler peripheries having gatings and said key plug having a groove formed in its periphery relatively to which said gatings are aligned when said tumblers are set by a properly bitted key, a side bar operatively positioned relatively to a locking groove formed in the bore outlining surface of said cylinder and also said key plug groove, the tumbler peripheries holding said side bar against full entry into said key plug groove until the tumbler gatings are placed in alignment with said groove whereby said side bar prevents free rotation of said key plug in said cylinder bore, said key plug groove having a shallow extension at the side thereof to permit said key plug to rotate relatively to said cylinder and side bar as permitted by said shallow extension, the said shallow extension not permitting the side bar to move into said tumbler gatings and out of said cylinder groove even if the tumbler gatings are aligned relatively to said shallow extension, whereby to require the return of said key plug to align its groove with said cylinder groove and the setting of said tumblers as a prerequisite to the release of said key plug for free rotation in said cylinder bore.

5. In a lock of the class described, a cylinder, a key plug rotatable in a bore of said cylinder, a series of tumblers rotatably mounted in said key plug on an axis parallel to the axis of rotation of said key plug and movable relatively thereto by a key so as to be positioned in accordance with the bittings of said key, said tumblers having gatings and said key plug having a groove in its periphery parallel to the axis of rotation of said key plug and relatively to which said gatings are aligned when said tumblers are set by a properly bitted key, a side bar operatively positioned relatively to a locking groove formed in the bore outlining surface of said cylinder and also said key plug groove, the tumblers holding said side bar against full

entry into said key plug groove until the tumbler gatings are placed in alignment with said key plug groove whereby said side bar prevents free rotation of said key plug in said cylinder bore, 5 said key plug groove having a shallow extension at the side thereof to permit said key plug to rotate relatively to said cylinder and side bar as permitted by said shallow extension, the said shallow extension not permitting the side bar to move into said tumbler gatings and out of said cylinder groove even if the tumbler gatings are aligned relatively to said shallow extension, whereby to require the return of said key plug to align its groove with said cylinder groove and the setting of said tumblers as a prerequisite to the release of said key plug for free rotation in said cylinder bore.

6. In a lock of the class described, a cylinder, a key plug rotatable in a bore of said cylinder, a series of tumblers carried by said key plug and movable relatively thereto by a key so as to be positioned in accordance with the bittings of said key, said tumblers having gatings adapted for alignment when said tumblers are set by a properly bitted key, a side bar operatively positioned relatively to a groove formed in the bore outlining surface of said cylinder and also a groove of said key plug adapted for the full entry of said side bar therein to release said key plug for rotation, 20 the tumblers holding said side bar against full entry into said key plug groove until said gatings are in alignment with said key plug groove through the proper positioning of said tumblers, said key plug groove having a shallow extension at each side thereof to permit said key plug to rotate relatively to said cylinder and side bar as permitted by said shallow extensions.

7. In a lock of the class described, a cylinder, a key plug rotatable in a bore of said cylinder, a series of tumblers carried by said key plug and movable relatively thereto by a key so as to be positioned in accordance with the bittings of said key, said tumblers having gatings adapted for alignment when said tumblers are set by a properly bitted key, a side bar operatively positioned relatively to a groove formed in the bore outlining surface of said cylinder and also a groove of said key plug adapted for the full entry of said side bar therein to release said key plug for rotation, 25 the tumblers holding said side bar against full entry into said key plug groove until said gatings are in alignment with said key plug groove through the proper positioning of said tumblers, said key plug groove having a shallow extension at each side thereof to permit said key plug to rotate relatively to said cylinder and side bar as permitted by said shallow extensions, the said shallow extensions being not as deep as said tumbler gatings whereby to hold the side bar out of said tumbler gatings and in said cylinder groove even if the tumbler gatings are aligned relatively to said shallow extensions, whereby to require the return of said key plug to align its groove with said cylinder groove and the setting of said tumblers as a prerequisite to the release of said key plug for free rotation in said cylinder bore.

8. In a lock of the class described, a cylinder, a key plug rotatable in a bore of said cylinder, a series of tumblers rotatably mounted in said key plug on an axis parallel to the axis of rotation of said key plug and movable relatively thereto by a key so as to be positioned in accordance with the bittings of said key, said tumblers having gatings and said key plug having a groove in its periphery parallel to the axis of rotation of said key plug

and relatively to which said gatings are aligned when said tumblers are set by a properly bitted key, a side bar operatively positioned relatively to a locking groove formed in the bore outlining surface of said cylinder and also said key plug groove, the tumblers holding said side bar against full entry into said key plug groove until the tumbler gatings are placed in alignment with said key plug groove whereby said side bar prevents free rotation of said key plug in said cylinder bore, said key plug groove having a shallow extension at the side thereof to permit said key plug to rotate relatively to said cylinder and side bar as permitted by said shallow extension, the said shallow extensions not permitting the side bar to move into said tumbler gatings and out of said cylinder groove even if the tumbler gatings are aligned relatively to said shallow extensions, whereby to require the return of said key plug to align its groove with said cylinder groove and the setting of said tumblers as a prerequisite to the release of said key plug for free rotation in said cylinder bore.

9. In a lock of the class described, a cylinder, a key plug rotatable in a bore of said cylinder, a series of tumblers carried by said key plug and movable relatively thereto by a key so as to be positioned in accordance with the bittings of said key, said tumblers having gatings adapted for alignment when said tumblers are set by a properly bitted key, a side bar operatively positioned relatively to a groove formed in the bore outlining surface of said cylinder and also a groove of said key plug adapted for the full entry of said side bar therein to release said key plug for rotation, a spring pressing said side bar toward said key plug groove, the tumblers holding said side bar against full entry into said key plug groove until said gatings are in alignment with said key plug groove through the proper positioning of said tumblers by said key, said key plug groove having a shallow extension at the side thereof to permit said key plug to rotate relatively to said cylinder and side bar as permitted by said shallow extension.

10. In a lock of the class described, a cylinder, a key plug rotatable in a bore of said cylinder, a series of tumblers carried by said key plug and movable relatively thereto by a key so as to be positioned in accordance with the bittings of said key, said tumblers having gatings adapted for alignment when said tumblers are set by a properly bitted key, a cylindrical pin operatively positioned relatively to a longitudinal groove formed in the bore outlining surface of said cylinder and also a longitudinal groove of said key plug adapted for the full entry of said side bar therein to release said key plug for rotation, a spring pressing said cylindrical pin toward said key plug groove, the tumbler peripheries holding said side bar against full entry into said key plug groove until said gatings are in alignment with said key plug groove through the proper positioning of said tumblers, said key plug groove having a shallow extension at the side thereof to permit said key plug to rotate relatively to said cylinder and

cylindrical pin as permitted by said shallow extension.

11. In a lock of the class described, a cylinder, a key plug rotatable in a bore of said cylinder, a series of tumblers carried by said key plug and rotatable relatively thereto by a key so as to be positioned in accordance with the bittings of said key, said tumblers having gatings and said key plug having a groove in its periphery relatively to which said gatings are aligned when said tumblers are set by a properly bitted key, a side bar operatively positioned relatively to a locking groove formed in the bore outlining surface of said cylinder and also said key plug groove, a spring pressing said side bar toward said key plug groove, the tumblers holding said side bar against full entry into said key plug groove until the tumbler gatings are placed in alignment with said key plug groove whereby said side bar prevents free rotation of said key plug in said cylinder bore, said key plug groove having a shallow extension at the side thereof to permit said key plug to rotate relatively to said cylinder and side bar as permitted by said shallow extension.
12. In a lock of the class described, a cylinder, a key plug rotatable in a bore of said cylinder, a series of tumblers carried by said key plug and rotatable relatively thereto by a key so as to be positioned in accordance with the bittings of said key, said tumblers having gatings and said key plug having a longitudinal groove in its periphery relatively to which said gatings are aligned when said tumblers are set by a properly bitted key, a locking pin operatively positioned relatively to a longitudinal locking groove formed in the bore outlining surface of said cylinder and also said key plug groove, a spring pressing said locking pin toward said key plug groove, the tumbler peripheries holding said locking pin against full entry into said key plug groove until the tumbler gatings are placed in alignment with said groove whereby said locking pin prevents free rotation of said key plug in said cylinder bore, said key plug groove having a shallow extension at the side thereof to permit said key plug to rotate relatively to said cylinder and locking pin as permitted by said shallow extension, the said shallow extension being not as deep as said tumbler gatings whereby to hold the locking pin out of said tumbler gatings and in said cylinder groove even if the tumbler gatings are aligned relatively to said shallow extension, whereby to require the return of said key plug to align its groove with said cylinder groove and the setting of said tumblers as a prerequisite to the release of said key plug for free rotation in said cylinder bore.
